GEAR-GRINDING MACHINE.

Application filed June 21, 1923. Serial No. 646,737.

This invention relates to a machine for finishing gear teeth after cutting or heat treating and has for its principal object to generate an accurate profile of the gear teeth so that the gears will run true and roll perfectly when in mesh. Heretofore, gear grinding machines as known have provided devices for automatically indexing the work at the end of predetermined lateral strokes of the work carrier and after the work has been moved to a point beyond the grinder element. Such a relation of parts requires a stroke of greater length than is necessary for the grinding operation and entails an appreciable loss of time in the grinding. In the improved machine movement of the work laterally is continued only so long as the grinder element is in operative relation to the work, the working strokes being of the shortest possible length and the indexing being done by withdrawing the work directly away from the grinding element at the end of predetermined working strokes. By this relation of parts the grinding operation is carried on continuously except during the indexing periods, the working stroke is shortened and the time ordinarily lost when the work is out of engagement with the grinder is eliminated. The result described is secured by mounting the work on a cross slide which is reciprocated laterally with respect to the grinder element and by mounting this work carriage on a table which itself may be moved directly outward away from the grinder at predetermined intervals to carry the work outward away from the grinding element when indexing is to be effected.

Another object of the invention is to provide in such a gear grinding machine simple and efficient devices for carrying on harmoniously and in proper co-ordination, the respective movements of the work carrying slide and the supporting table whereby the indexing may be brought about automatically in proper relation to the movements of the parts.

Still another object of the invention is to incorporate in such a machine means which are also co-ordinated with the above described devices for raising and lowering the supporting table with its cross slide with a step by step movement at the end of predetermined working strokes so that, when necessary, gear teeth of broad faces or the teeth

of a plurality of superimposed gears may be finished before the work is indexed for the grinding of other teeth, the effect being to draw the work across the grinder. These devices include generally a vertical slide on which the above described work table and cross slide are mounted, a screw for raising and lowering the said vertical slide, and an intermittently operable ratchet for rotating the operating screw in proper relation to the other movements of the machine.

Other features of the invention have to do with improved means for mounting rotary grinders adjustably on the frame of the machine and in such relation to one another and to the work as to function simultaneously and effectively for grinding different faces of the work, such as different faces of two teeth of a gear.

Still other features of the invention are concerned with details of construction which make all of the operating parts simple, accessible, rugged and invariable in operation.

The broad principles involved in the invention will be better understood with reference to the detail description of the preferred embodiment thereof illustrated in the accompanying drawings wherein:

Figure 1 is a view in front elevation of the machine showing generally the relation between the vertical slide, the sliding table thereon, the work carriage slidable transversely of the table, the work support thereon, and the grinding elements.

Figure 2 is a view in plan of the machine shown in Figure 1.

Figure 3 is a view in side elevation thereof.

Figure 4 is a detailed view on a somewhat larger scale showing the mounting of the rotary grinding elements.

Figure 5 is a detailed view in side elevation of the mounting for the truing device for one of the grinders.

Figure 6 is a detailed view in side elevation of the actuating ratchet for turning the screw which moves the vertical slide.

Figure 7 is a view partly in horizontal section and partly in plan of the elements shown in Figure 6.

Figure 8 is a view in plan of the parts shown in Figure 6.

Figure 9 is a fragmentary view in elevation of one of the actuating pawls of the ratchet.

Figure 10 is a view in plan showing particularly the devices for effecting movements of the work table periodically for carrying the work away from the grinder element for indexing.

Figure 11 is a fragmentary view partly in vertical section through the pitman and sliding abutment illustrated in Figure 10 for throwing the table out for indexing.

Figure 12 is a view in transverse section through some of the parts shown in Figure 11 for throwing out the table for indexing; while Figure 12^a shows diagrammatically the relation of parts when the table is thrown out.

Figure 13 is a fragmentary view partly in section and partly in elevation showing the supporting chuck for the work spindle and the bands for imparting a rolling movement thereto upon reciprocation of the work carriage.

Figure 14 is a transverse view in horizontal section through the chuck shown in Figure 13 and taken on the plane indicated by the line 14-14 of Figure 13 and looking in the direction of the arrows and indicating particularly the holding pawl which is automatically thrown out when the chuck is rotated for indexing.

Figure 15 is a view in vertical section through the parts shown in Figures 13 and 14 but taken on the plane indicated by the line 15-15 of Figure 13 and looking in the direction of the arrows.

35 Grinding Elements and Truing Devices.

Before proceeding with the description of the means for automatically presenting the work in proper relation to the grinding elements and for indexing it periodically a description of suitable grinding elements for finishing the work accurately and their mounting on the frame of the machine and of suitable truing devices which are prefer-

ably mounted in operative relation to the grinding elements, will be given. The base *a* of the machine has mounted thereon vertical standards *a'*, *a''*, to which are secured adjacent their upper ends a cross member

50 *b*. The cross member *b* carries on its front face a transverse way *b'* on which is supported slidably brackets *c*, *c'*, movable transversely by independent adjustable screws *c²*, *c³*, respectively, journaled on the vertical standards *a'*, *a''*, and engaging the respective sliding brackets. On the brackets *c*, *c'*, are mounted swiveled plates *c⁴*, *c⁵*, respectively, the angular positions of which may be adjusted by bolts *c⁶*, *c⁷*, respectively,

55 engaged with the respective brackets *c*, *c'*, and passing through slots *c⁸*, *c⁹*, in the respective plates. On the angularly adjustable plates *c⁴*, *c⁵*, are mounted slides *c¹⁰*, *c¹¹*, respectively, which may be moved independently on their ways by hand-wheels

c¹² carried on work screws *c¹³* operatively engaged with the respective slides. On the slides *c¹⁰*, *c¹¹*, are secured journal bearings *c¹⁴* in which are journaled supporting shafts *c¹⁵* for the grinding wheels *c¹⁶* which, by 70 the construction described, are mounted in opposed relation as indicated clearly in Figure 4. Power for rotating the grinding wheels may be applied through pulleys *c¹⁷* carried on their respective shafts. 75

The form and construction of the grinding wheels *c¹⁶* constitute no part of the present invention and grinding elements having other characteristics may be employed in the machine without departing from certain of the claims appended hereto. When the wheels are of the truncated conical form illustrated it may be convenient to associate therewith a gauge element for facilitating their setting so that the grinding edge face 85

will function in proper relation to the pressure line of the particular element being ground. To this end, there is mounted on the cross member *b* a bracket *d* which carries an adjustable slide *d'* with which may be 90 carried a positioning member *d²* having oppositely inclined side edges of proper angularity and movable into engagement with a tooth or teeth of the gear to determine its initial setting in proper relation to the grinder wheels. With such a setting, for instance, proper grinding is assured. For setting the grinding wheels with the proper angularity for grinding the gear teeth a loose gauge element *d³* of the form indicated in dotted lines in Figure 4 may be placed on the positioning member *d²* when the latter is projected. The gauge element *d³* may have beveled faces *d⁴*, *d⁵*, which form an included angle and against which the grinding edges of the respective wheels rest flatly when the wheels are properly set for the grinding of teeth having a predetermined pressure angle. 95

It is proposed in the preferred form of the invention to mount on the bracket *d* and in proximity to the respective grinding wheels *c¹⁶* truing devices which may be conveniently manipulated for truing either one of the wheels as required. Such devices are shown as comprising rocking bell crank levers *e* pivoted respectively in swiveled supports *e'* carried on the bracket *d*, one arm of each of the bell cranks being formed as an handle *e²* and the other arm carrying a diamond point *e³*. The mounting is such that when either bell crank *e* is rocked the diamond point is moved in a plane parallel to the grinding face of the proximate wheel *c¹⁶*. The wheel may have its grinding face drawn into engagement with the diamond when thus swung by moving the supporting slide *c¹⁰* or *c¹¹* as the case may be. No matter how the cutting face is worn, accordingly, it will be trued off in the proper plane for continued 110 115 120 125 130

grinding of the work. The diamonds after this initial setting remained fixed and serve as gauge members against which the grinding wheels are drawn to determine their proper position from time to time with reference to the work, the wheels being movable against the diamonds. It is preferred to have the axis of the cutting diamond disposed somewhat angularly to the cutting face to be trued so that the diamond will be worn at one side when moved to and fro across the face. The support for each diamond in the arm of the bell crank *e* is such that it may be rotated on its own axis from time to time to present an unworn portion for the next truing operation.

Support for the work and devices for imparting desired movements thereto.

20 Co-operating with ways *a*³ carried with the vertical standards *a'*, *a*², (Figure 10) is a vertically reciprocable slide *f* which may be formed with a forwardly extending horizontal support *f'* for the slides to be described. The vertical slide *f* may be counterbalanced by weights *g* connected thereto in any suitable manner by cords *g'* passing over pulleys *a*⁴ supported on the vertical standards *a'*, *a*², these standards, if desired, 25 being hollow, to receive the weights.

The horizontal section *f'* of the vertical slide *f* is formed with ways *f*² at its opposite sides to co-operate with a slide *h* which is adapted to move in and out with respect to 30 the grinding elements at predetermined times when the work is to be indexed. The slide *h* is formed on its upper surface with transverse ways *h'* to receive the transversely reciprocable work carriage *i* which slides 35 transversely of the grinding element to present the work properly thereto for grinding.

The work which is to be supported in operative relation to the grinding elements is illustrated in the drawings as a spur gear. 40 Such work may be mounted on the work carriage in a hub *i'* fixed to the slide *i*. As shown in Figures 13-15 the hub *i'* may support a bushing *i*² in which is rotatably mounted a hollow work spindle *i*³ which 45 may be changed as necessary to receive adapters of various sizes on which the work is carried. The hollow work spindle *i*³ has keyed to its lower end as at *i*⁴ a gear *i*⁵ by which indexing is effected at predetermined 50 times in a manner to be described.

The slide *i* is constantly reciprocated transversely of the grinding element, during operation of the machine by means of a pitman *k* illustrated as a forked rod pivoted to 55 the slide as at *k'* and pivoted at its other end to a crank disk *k*² by means of a crank pin carried on a slide *k*³ which is adjustable in the crank disk *k*² along a diameter thereof whereby the radius on which the connecting 60 crank pin rotates may be varied to change

the amplitude of travel of the work slide *i* as may be necessary. The crank disk *k*² is supported on a shaft *k*⁴ journaled in the vertical slide *f* and connected through double universal joints *k*⁵, *k*⁶, and a telescoping 70 shaft section *k*⁷ with a driving gear *k*⁸ connected operatively with the main source of power.

Movements of the slide *h* in and out with respect to the grinding element when indexing is to be effected at predetermined times, is accomplished through a pitman *l* pivoted at *l'* to the work slide *i* and at its other end to a slide *m* through a pin *m'* carried thereby, the slide *m* being reciprocably mounted 75 for movement in and out on a permanently adjustable slide *n* carried on the vertical slide *f*, which slide *n* is adjustable initially by means of a screw *n'* having a hand-wheel *n*² at the front of the machine for adjustment. During the grinding operation, when the work slide *i* is reciprocated transversely by the pitman *k* the supporting slide *h* will have no tendency to move in and out. The 80 arm *l* will swing back and forth and the slide *m* may be reciprocated in and out on the slide *n* as the pin *l'* travels in a straight line.

Indexing.

In connection with the indexing operation the conventional means for causing the work to oscillate on its spindle when moved back and forth with relation to the grinding element should be understood. The slide *h* has depending arms *h*² at opposite sides thereof to which are secured adjustably the free ends of Bilgram bands *o*, *o'*, the inner ends of which are fastened at opposite sides to the periphery of a drum *p*. This drum is secured to a hollow shaft *q* which carries a radially extending arm *q'* in which is slidably mounted a spring-pressed pawl *q*² for the purpose which will later appear. The pawl *q*² under the influence of a spring *q*³ normally engages the indexing gear *i*⁵ which, as has been described, is keyed to the hollow work spindle *i*³. By the engagement 100 of the pawl *q*² with the indexing gear *i*⁵ oscillations of the drum *p* under the influence of the Bilgram bands *o*, *o'* upon lateral reciprocations of the work slide *i* are 105 imparted to the work spindle *i*³ and to the work so that it is rolled with proper relation to the grinding element or elements in 110 a manner which will be understood by one skilled in the art.

It is proposed in accordance with the present invention to limit the transverse reciprocations of the work slide *i* to the extent necessary to insure uninterrupted grinding during each work stroke with no additional lost motion. The amplitude of this stroke, as has been pointed out hereinbefore, is determined by the adjustment 115 120 125 130

of the slide h^8 for the crank pin of the arm k in the crank disk k^2 . Heretofore, it has been the common practice in grinding operations to reciprocate the work table a sufficient distance each stroke to carry the work wholly out of engagement with the grinding element and then, effect the indexing while the work is beyond the grinding element. This involves considerable loss of time. By 10 the present invention it is proposed to move the slide h away from the grinding element at predetermined times for indexing. Such a movement of the slide will, of course, carry with it the work slide i which is mounted on 15 it and the work. In order to force the slide h outwardly in this manner suitable means are indicated in Figures 10-12. In the slide n is mounted a transverse locking slide n^{10} which preferably has a spring n^{20} back of it 20 tending always to force the slide in rear of the slide m so as to hold the latter against reciprocation. However, the slide n^{10} is normally held out of the path of the slide m by means of a slide n^{30} which is normally 25 forced in the opposite direction by means of a spring n^{40} . A slot and pin connection may be interposed between the slide n^{30} and the throw out slide n^{10} so that when the slide n^{30} is projected the slide n^{10} will be 30 out of the path of the slide m and yet the slide n^{30} may move inwardly relatively to the slide n^{10} , thereby compressing the spring n^{20} before the slide n^{10} snaps in behind the slide m which may occur when the latter is 35 in its forward position. On the inner face of the standard a^2 may be mounted adjustably a stop a^5 which is engaged periodically by a roller n^{50} mounted on the end of the slide n^{30} . As will be described later, vertical 40 step by step reciprocations may be given to the slide f for the purpose of carrying the grinding elements over the entire surface which is to be ground and it is at the end of certain of these step by step movements 45 that the roller n^{50} will run onto the stop a^5 so as to move the slide n^{30} inwardly and place the spring n^{20} under compression. With the parts in such position, at the end 50 of one of the transverse reciprocations of the work slide i , the connecting arm l will draw the slide m forwardly to a position where the locking slide n^{10} may snap in behind it. During the next reciprocation of the sliding work table i the slide m will 55 be held against rearward movement thereby fixing the pin m' relatively and, when the arm l starts to swing, forcing the slide h outwardly and with it, of course, the slide i which is carried thereby and the work. 60 In this manner, the work is carried out of engagement with the grinders. With the parts in this relation the indexing is effected, that is to say, the angular position of the work spindle i^3 is permanently changed so 65 as to bring other parts of the work, such

as other gear teeth, into position for grinding. To accomplish this in the most convenient manner it is desirable to disconnect the pawl q^2 from the gear i^5 momentarily without interfering with the action of the 70 Bilgram bands on the drum p so that the arm q' will continue to swing and when the pawl q^2 is re-engaged with the gear i^5 it will engage another tooth thereof. The work slide i carries a bracket r which is 75 supported on two rods r' journaled in the work slide and free with respect thereto so that the slide may move in and out during indexing without hindrance. The rear ends of the rods r' are connected by means of a 80 T-head r^2 engaged by a slide r^3 fixed through a distance rod r^4 to the slide n (Figures 10-15). On the bracket r is supported a cam s carried on a pivoted arm s' journaled on a pin s^2 which is engaged operatively by a suitable spring s^3 to hold the cam yieldingly in desired relation to a roller 85 q^4 on the pawl q^2 for co-operation in a manner which will later appear.

On the bracket r is also pivotally mounted 90 a brake arm t pivoted at t' and normally held in retracted position by a spring t^2 to maintain the braking element t^3 out of engagement with the teeth of the indexing gear i^5 . The braking element t^3 may be 95 moved yieldingly into engagement with the teeth by means of a pivoted follower t^4 which is backed by a spring follower t^5 . The free end of the brake lever t is also 100 disposed with respect to the path of the roller q^4 during indexing as to be actuated thereby for application of the brake during that period of time when the pawl q^2 is disengaged from the indexing gear. Consider now the operation of the parts described. The bracket r with the cam s is 105 normally maintained in fixed relation to the work table so that transverse reciprocations of the work table during grinding operations will carry the roller q^4 to and fro 110 back of the cam s . When, however, the locking slide n^{10} snaps in behind the slide m in the manner hereinbefore described the pitman l will swing about a fixed center and during the next lateral reciprocation 115 of the work slide i cause this slide with the work to be carried outwardly away from the grinding element. This outward travel combined with the transverse movements will carry the roller q^4 along the face of the cam s so that the pawl q^2 is withdrawn 120 for engagement from the indexing gear i^5 . In proper timed relation to that action, the roller q^4 presses against the brake arm t so as to throw the brake element t^3 yieldingly against the gear teeth of the indexing gear so that it will be snapped into engagement with one of the teeth by the action 125 of the follower spring t^5 when in alignment with one of the teeth. The indexing gear 130

is thus held permanently against accidental displacement during the period of time when the pawl q^3 is out of engagement with it and being carried into position for re-
 5 engagement permanently with another tooth. When the roller q^4 has run off of the cam s in the manner described the pawl will be snapped back into engagement with another tooth as is evident and pressure on
 10 the brake arm t will be relieved so that the spring t^2 is free to retract the braking element for subsequent oscillation of the gear under the influence of the oscillating arm q' . On the reverse stroke with the pit-
 15 man still swinging about its fixed center the work slide i will be slowly retracted as the radius shortens. Accordingly, the roller q^4 will run against the arm s' which carries the cam s and this arm will yield
 20 angularly on its pivot pin against the action of the spring s^3 and be restored to normal operating position against its abutment after the roller q^4 has been thrown wholly out of engagement with it. At the end of
 25 this said reverse stroke the work slide i will end up in position to start the next succeeding work stroke and at that instant the locking slide n^{10} will be moved out of engagement with the slide m under the influence of the predominant spring n^{10} , as described. Subsequent reciprocations of the work slide will carry that portion of the work then presented for grinding in proper relation to the grinding elements.
 30 The path of travel of the work slide during indexing and during normal grinding operations is indicated diagrammatically by the views shown in Figure 12^a.

40 *Vertical feed devices.*

Improved devices are provided for imparting a step by step vertical movement to the slide f either upwardly or downwardly, as required, and these devices are characterized by compactness, simplicity, accessibility and the positive nature of their actuation of the slide. Generally speaking, they comprise a ratchet wheel which is driven by one of two pawls adapted to be reciprocated through connecting rods, respectively, pivoted to a rotating crank disk, the pawls being thrown into and out of operative engagement with the ratchet wheel automatically by stops which are susceptible of adjustment to insure this engagement at predetermined times with respect to each of the pawls so that not only will the slide be moved in the desired direction but will be moved in that direction during predetermined periods. Referring particularly to Figures 6-9 it appears that a rotating disk u which may receive its movement through a sprocket u' engaged by a chain u^2 (Figure 3) driven from the main power shaft u^3 , has pivotally connected thereto as

at u^4 two connecting rods u^5, u^6 , which are pivotally connected to opposed oscillating arms u^7, u^8 , respectively, at opposite sides of their axis of oscillation. These arms u^7, u^8 , have extended concentric hubs u^9, u^{10} , respectively, which are journaled on a hollow hub v of a ratchet disk v' . On the arms u^7, u^8 , are pivoted pawls u^{11}, u^{12} , respectively, the noses of which are adapted to co-operate with the ratchet disk v' and the tails of which are formed with notches u^{13} for engagement by spring-pressed detents u^{14} carried in the ends of the arms u^7, u^8 , and adapted to maintain the pawls yieldingly in any one of three positions for the purpose which will appear later. Each pawl u^{11}, u^{12} , has an extended bearing hub one of which u^{15} is shown in Figure 8 and with the hub is formed a depending finger u^{16} for co-operation with stops whereby the respective pawls are moved automatically into and out of engagement with the ratchet disk v' . The hub v of the ratchet disk v' is keyed to a shaft w which has an extended section w' of reduced diameter on which is mounted loosely the hub x of a separate disk x' , the periphery of which is formed with a circumferential undercut slot to receive the T-heads x^2 of stops x^3 which are adjustable manually around the slot for the purpose of tripping the respective pawls at predetermined times to insure the desired actuation of the ratchet disk v' and through it of the vertical slide f . The stop disk x' has an open face and an internal gear x^4 cut on its inner periphery for engagement by planetary pinions y which rest within the open face and are journaled on short shafts y' , respectively, bolted through a disk y^2 having an extended hub y^3 loosely mounted on an extended hub z of a pinion z' which is also engaged by said pinions. The hub z is keyed to the shaft section w' of reduced diameter so that rotation of the shaft imparts a rotative movement to the stop disk x' through the planetary gearing described but at considerable reduction to the end that the stop disk x' shall rotate at considerably less speed but in predetermined timed relation to the ratchet disk v' . The shaft section w which is keyed to the ratchet disk v' and is rotated by the direct action of the ratchet disk may be journaled as at w^2 in the frame a of the machine and carry a spur gear w^3 which is meshed with the pinion w^4 on a shaft w^5 which is arranged to drive the vertically disposed lift screw w^6 for the vertical slide f , as through further reduction bevel gears w^7, w^8 .

In the operation of the vertical feed devices above described it is to be remembered that the disk u has continuous unidirectional rotary movement and thereby effects continuous reciprocation of the connecting

rods u^5 , u^6 and continuous oscillation of the pawls u^{11} , u^{12} . The respective stops x^3 for the pawls co-operate with their fingers u^{18} at such times as to engage one of the 5 pawls with the ratchet wheel while throwing the other pawl out of engagement therewith, depending upon direction of movement of the slide f desired. When once engaged the spring-pressed detents u^{14} will hold the pawls in the positions into which they are positively thrown by the stops and fingers and their condition will remain unchanged until such time as other appropriate stops are brought into engagement 10 with said fingers through the slow rotary movement of the stop disk x' to change the condition, as by disengaging one pawl and throwing in the other. The effect of such a reversal necessarily effects a reversal in 15 the direction of travel of the slide f as is desirable in accordance with the method of grinding employed. The action is positive at all times. It is certain in that the pawls pick up the ratchet disk quickly for 20 actuation of the slide in exact predetermined timed relation to the other movements of the machine. The driving mechanism is self-contained in a more or less unitary sense, the parts thereof are accessible and the desired timing may be accurately determined by manual adjustment of 25 the stops in the stop disk x' . Aside from the automatic operation obtainable by these devices they lend themselves to manual actuation of the vertical slide f as through application of a wrench or other suitable tool to the extended hub z which may be of irregular external cross section. When 30 any such manual operation is to be effected it is desirable to throw the pawls u^{11} , u^{12} away from the ratchet disk v' to a point beyond where their fingers may be engaged by the stops x^3 , one of the notches u^{13} in 35 the tails of the pawls making it possible to retain them in this remote position through the detents u^{14} .

The principle involved in the grinding has been described fully hereinbefore and it is to be understood that the invention 50 in a broad sense is concerned primarily with devices which lend themselves to the practice of grinding in accordance with this principle rather than in the details of construction of the parts illustrated in the accompanying drawings. It will be evident to one skilled in the art, for instance, that other mechanical movements than those described may give, with some degree of commercial operation satisfactory results although differing in form and arrangement 55 from the illustrated embodiment. Any departures in matters of design and arrangement of elements are to be deemed within the spirit of the invention so long as the 60 results described are secured by means

which act generally in accordance with the novel principle underlying the method.

What I claim is:

1. In a gear grinding machine, in combination with the frame and rotary grinding element, a work carrying slide movable transversely of the grinding element, a spindle on which the gear is mounted, opposed bands connected to the spindle and adapted to impart a rolling motion thereto 75 upon transverse movements of the slide, means to arrest movement of the slide at a point when the work is about to leave the grinding element and means to move the work laterally away from the grinding element to disengage the work from the grinding element for indexing during predetermined strokes.

2. In a gear grinding machine in combination with the frame thereof, a work 85 supporting table carried with the frame and means to move the work table away from the grinding element, said means including a connecting rod connected with the table, a slide pivoted to the connecting rod and movable freely, means to lock said slide periodically to fix one end of the said connecting rod, and means to swing the connecting rod about said fixed end as a center.

3. In a gear grinding machine, in combination with the frame and grinding element, a work carrying slide, means to reciprocate the slide laterally with respect to the work, a work carrying table on which the slide is mounted, a connecting rod pivoted to the slide, a locking slide pivoted to the free end of the connecting rod and normally reciprocable freely upon lateral reciprocations of the work carrying slide and means to hold said locking slide against such reciprocations during predetermined strokes of the work carrying slide.

4. In a gear grinding machine, in combination with the frame and grinding element, a work carrying slide, means to reciprocate the slide laterally with respect to the work, a work carrying table on which the slide is mounted, a connecting rod pivoted to the slide, a locking slide pivoted to the free end of the connecting rod and normally reciprocable freely upon lateral reciprocations of the work carrying slide and means to hold said locking slide against such reciprocations during predetermined strokes of the work carrying slide, such means including spring-loaded plungers movable into position behind said locking slide and means carried with the frame to force such spring-loaded plungers into such position.

5. In a gear grinding machine in combination with the frame and grinding element, a work carrying table movable vertically with respect to said frame power means to move said table automatically at predetermined times and weights to counterbal-

ance said table during its vertical movements.

6. In a gear grinding machine in combination with grinding elements and the frame on which they are supported, a slide movable vertically in said frame, a work carrying slide mounted on the first named slide, means to reciprocate the work carrying slide laterally away from the grinding element for indexing and means operable in predetermined relation to said lateral reciprocations of the work carrying slide to move the vertical slide.

7. In combination with a driving shaft and a driven shaft transmission devices adapted to transmit uni-directional rotation of the drive shaft to the driven shaft to rotate it in different directions for predetermined periods of time including a revolving crank pin carried with the power shaft, connecting rods pivoted to the pin, arms journaled on the driven shaft, means to connect the said connecting rods pivotal to the respective arms at opposite sides of the driven shaft, pawls pivoted on said arms, a ratchet wheel keyed to the driven shaft and adapted to be engaged operatively by one or the other of said pawls and means to throw the said pawls into and out of engagement with said ratchet wheel automatically at predetermined times.

8. In a machine of the character described in combination with a uni-directional rotating driving shaft, a revolving crank pin carried therewith, connecting rods pivoted to the crank pin, a driven shaft, means to automatically drive the driven shaft from the driving shaft in different directions during predetermined periods, and including pawls supported operatively on the driven shaft at opposite sides thereof, means to pivot the connecting rods operatively with the respective pawls, a ratchet wheel connected with the driven shaft and adapted to be engaged operatively by one or the other of said pawls for rotating the shaft in one direction or the other, a rotating tripping element mounted loosely on the driven shaft in proximity to the said ratchet wheel and having stops adapted to engage the pawls periodically and planetary gearing interposed between the driven shaft and the rotating tripping element whereby the latter is driven at a predetermined speed ratio to the ratchet wheel.

9. In a gear grinding machine in combination with a frame and grinder element, a slide movable vertically on the frame to carry the work across the grinding element, and means to impart a step by step movement upwardly and downwardly to said slide, said means including a hoisting screw, a driving shaft, and means interposed operatively between the hoisting screw and the driving shaft to impart rotary move-

ment to the screw in first one direction and then the other at predetermined times.

10. In a gear grinding machine in combination with a grinder element, a work carrying slide adapted for reciprocation laterally away from the grinding element for indexing, a spindle on the slide to carry the gear, opposed bands to impart a rolling movement to the gear during lateral reciprocations of the slide, an operative connection between the spindle and the bands, and means apart from said operative connection to interrupt said connection periodically for indexing.

11. In a gear grinding machine in combination with the frame and grinding element, a slide to carry the work laterally away from the grinding element for indexing, a spindle on the slide, a gear carried with the spindle, a drum carried with the slide, opposed bands connected to the drums to impart a rolling movement thereto upon said reciprocations of the slide, a pawl carried with the drum and engaged with the gear on the spindle, and means apart from the drum and associated mechanism to withdraw the pawl from the gear periodically for indexing.

12. In a grinding machine, in combination with a grinder element and work spindle, a work carrying slide adapted for reciprocation transversely with respect to the grinding element, a frame supported on the slide, means to move the slide laterally away from the grinder element and means mounted on the frame to hold the work spindle against movement during such movement of the slide.

13. In a grinding machine, in combination with a grinder element, a work carrying slide adapted for reciprocation laterally with respect to the grinding element, means to impart a rolling movement to the gear during such reciprocations of the slide including an oscillating pawl engaged with the gear support, a cam supported normally out of the path of said oscillating pawl, and means to move the slide with respect to the cam and away from the grinder element to bring the pawl into operative relation to the cam at predetermined times for momentary disengagement of the pawl from the gear support.

14. In a grinding machine, in combination with a grinder element, a work carrying slide adapted for reciprocation laterally with respect to the grinding element, means to impart a rolling movement to the gear during such reciprocations of the slide including an oscillating pawl engaged with the gear support, a cam supported normally out of the path of said oscillating pawl, means to move the slide with respect to the cam and away from the grinder element to bring the pawl into operative rela-

tion to the cam at predetermined times for momentary disengagement of the pawl from the gear support, and means supported with the cam to hold the gear support against movement during disengagement of the pawl therefrom.

15. In a gear grinding machine, in combination with a grinder element, a work carrying slide adapted for reciprocation laterally with respect to the grinding element, a spindle on the slide to carry the gear, a gear carried with the spindle, an oscillating pawl engaged with the last named gear, opposed bands to impart an oscillating movement to the pawl, a frame

carried with the slide, a cam supported on the frame, means to move the slide away from the grinder element at predetermined times to bring the pawl into engagement with the cam for momentary disengagement of the pawl from the second named gear, and a brake element supported on the said frame and engageable with the said second named gear upon disengagement of the pawl therefrom, and under the influence of the said oscillating arm.

This specification signed this 18th day of June A. D. 1923.

GOTTFRIED WIRRER.
